UNITED STATES PATENT OFFICE.

MELVILLE E. PETERS, GEORGE H. FATH, AND ALBERT F. MILLER, OF DENVER,
COLORADO.

BOX-FEEDING MECHANISM FOR BOX-WRAPPING MACHINES.

1,229,512.

Specification of Letters Patent. Patented June 12, 1917.

Application filed April 28, 1916. Serial No. 94,207.

To all whom it may concern:

Be it known that we, MELVILLE E. PETERS, GEORGE H. FATH, and ALBERT F. MILLER, citizens of the United States of America, residing in the city and county of Denver and State of Colorado, have invented a new and useful Box-Feeding Mechanism for Box-Wrapping Machines, of which the following is a specification.

10 Our invention relates to an automatic box feeding mechanism for feeding unwrapped paste board boxes to box wrapping machines; and the objects of our invention are:

First, To provide a feeder for box wrapping machines in which the boxes are placed by an attendant, and which automatically feeds the boxes intermittently in registering relation to the box supporting plunger of a box wrapping machine. And

20 Second, To provide an automatic box feeder that will feed straight sided and extension edge boxes either with or without stayed corners, to the box supporting plunger of box wrapping machines.

25 We attain these objects by the mechanism illustrated in the accompanying drawings, in which:

Figure 1, is a side view of a portion of a box wrapping machine, showing the application thereto of the improved automatic box feeder.

Fig. 2, is a central, vertical, transverse, sectional view through the machine and box feeding mechanism shown in Fig. 1.

35 Fig. 3, is a plan view of the box feeding mechanism.

Fig. 4, is a vertical sectional view, enlarged, on the line 4-4 of Fig. 3. And

40 Fig. 5, is an end view of one of the box guide bars, showing the box stop mounted thereon.

Similar letters of reference refer to similar parts throughout the several views.

Our box feeding mechanism can be arranged to be attached to any box wrapping machine. We have preferably illustrated it however attached to a fragment portion of the box wrapping machine illustrated in our pending application Serial Number 50 59,860, filed November 5, 1915.

Referring to the drawings,—

Fig. 1 designates our improved box feeding mechanism, and in this view as well as the other figures of the drawing the

55 numeral 1 designates the base plate, 2 designates the end frames, 3 the side frames, and 4 a top table portion of the fragment of the wrapping machine above referred to.

Between the side frames a main driving shaft 5 is journaled in suitable bearings 6 that are secured to the base plate. This shaft extends longitudinally of the machine, and is adapted to be connected to and rotated by power supplying and transmitting mechanism, which we do not illustrate. 65

Upon the main shaft 5 we secure a cam 7, having a groove in which lies a roller 8 that is mounted on a yoke or fork end 9, which is bolted to the lower end of a lever 10. The fork end 9 straddles the main shaft 60 5 and the upper end of the lever 10 is secured by a bolt to a projection 11 adjacent to the lower end of a lever 12. The lower end of this lever is pivotally secured upon a stud secured to a bracket 13, which is 70 bolted to the table. The upper end of this lever is pivotally connected to one end of a link 14, the opposite end of which is pivotally attached to a depending lug 15, that is secured to a slide bar 16 that is reciprocally 75 mounted in a slideway 17 that is formed in a ribbed bar 18 that extends at right angles to the longitudinal axis of the box wrapping machine and from its upper and lower plungers 19 and 20 respectively. 85

This ribbed bar is supported upon and secured to a cross bar 21 that is secured at one end to a bracket 22 that is bolted to the top of the table, and is supported by a bracket 23 at its other end that 90 is bolted to the yoke-shaped frame 24. The ribbed plate is provided with a slot 25 through which the lug 15 depends, and the slideway is formed partially in each of two opposite upwardly projecting ribs that 95 extend along its length. An adjustable flanged push bar 26 is secured upon the top of the slide bar 16, by a bolt 27, which passes through a slot 28 in the push bar, and is screwed into the slide bar. To the 100 forward end of the push bar 26, is secured a plate 29, the upper edge of which is backwardly curved, which permits an attendant to rapidly place the boxes with accuracy upon the slideway and against the said 105 plate 29 without striking the top edge of it. This box pusher works reciprocally to feed a box-shell, which means a stayed or

unstayed corned box in an unwrapped condition to the upper plunger of the box wrapping machine, at each cycle of its operative movement, as will be fully explained hereinafter.

This box pushing bar and its supporting bar are on a horizontal plane, and at right angles to and centrally of the length of the plungers 19 and 20.

16 The cross bar 21 supports at its opposite ends guide bars 30, each of which is integrally connected to a slide block 31, which is adjustably mounted on the said cross bar, by means of bolts 32, which pass through 15 the said slide blocks and through slots 33 formed in the cross bars.

These guide bars 30 form the side gages for the boxes and they are adjustable to and from the longitudinal center of the slideway plate and its box pushing bar to fit boxes of varying lengths. They are consequently adjusted to receive the size of boxes that are to be fed to the plunger loosely but snugly between them, and are then bolted in their 25 adjusted positions. To facilitate the rapid and accurate placing of boxes one after the other by an attendant, the guide bars are each provided along their upper edges with a backwardly curved blade 34, which is secured to each guide bar by any suitable means. These guide bars and the slideway bar are positioned in such relation to the upper plunger that the reciprocating box pusher delivers them directly and centrally 30 under the plunger, and a stop 35 is adjustably secured on the inner end of each guide bar against which the box is moved by the pusher bar. Each stop comprises a yoke-shaped member that straddles the top edge 35 of the guide bar, and which present abutments which define the inward movement of the boxes relatively to the plungers.

The guide bars 30 are each formed with a horizontal ledge 36, which ledges are on the 40 same plane as the upper face of the slideway bar 18, and form with the said slideway bar supporting means for the boxes, as will be clearly understood by reference to Fig. 1.

Our box feeding mechanism will feed 45 either plain, straight sided boxes, or extension edge boxes, having either stayed or unstayed corners, and the guide bars extend along the opposite ends of the plunger and guide the boxes centrally to it. The ledges 50 36 are only slightly longer than the width of the largest box for which the machine is set; and it is therefore necessary that means be provided for supporting the boxes in a position between the two plungers, and that 55 such supports be capable of being automatically withdrawn, in order that the boxes may be carried down with the upper plunger, to pass between the side wipers; supports of this character being necessary in the 60 case of extension edge boxes, where if pres-

sure upon the boxes were required to spread the supports, the extended edges would thereby be broken.

To this end, we provide each of the guide bars 30 with two integral brackets 37, the upper ends of which are provided with bearings in which a shaft 38 is rotatively mounted. Each shaft extends beyond the end of the outer bearing and a coiled spring 39 is mounted on it, one end of which is secured to a collar that is secured to the end of the shaft, and the other is secured to the adjacent bearing. A lever 40 is mounted on and is secured to each shaft 38 between its 75 bearings, and its opposite end is adjustably secured to the slotted end of a slotted bar 41 by a clamping bolt 42.

Each slotted bar is provided at its inner end with a roller 43 which when the plunger 19 is at the limit of its upper stroke bears against its adjacent ends, and the slot allows for adjustment of the bar relative to the length of plunger as will be presently described.

To the opposite end portions of the shafts 38 inside the bearings 37, levers 44 are secured, the lower ends of which are pivotally secured to one of the ends of a pair of links 45, the opposite ends of which are pivotally secured to opposite ends of blades 46, which are reciprocally supported in slots 47 formed through each of the guide bars 30. The rollers 43 bear on opposite ends of the plunger when it is at the limit of its up stroke, and the said rollers are automatically held against the ends of the plunger by the tension of the springs 39. A cam blade 48 is secured on top of and at each end of the upper plunger, and the springs 39 are arranged to exert a tension on the shaft that turns it to cause the rollers of the bar to bear with a resilient pressure against the opposite ends of the plunger, and as long as the rollers are on the plunger the blades are held inward beneath the bottom of the box, and thus support the said boxes. As the plunger moves down it enters the box and when it gets within about a quarter of an inch of its inside bottom surface, the rollers 43 on the bars 41 ride onto the backwardly curved cam blades 48, which allows the springs to turn the shaft to draw the blades 46 back away from under the bottom of the box and instantly afterward the plunger reaches the inside surface of the bottom of the box and carries it down against the blank and against the lower plunger.

The operation is as follows:

An attendant places the uncovered boxes one at a time on the supports formed by the ledges 36 and the slideway bar, between the side blades 34 and the guide bars 30, and in front of and against the box pushing blade 29. Then the reciprocating box pusher blade, which is timed by the cam and lever 130

mechanism, moves each box under the upper plunger 19 of the first stage treatment station of the box wrapping machine, just as it reaches the limit of the upper stroke of its vertical reciprocating movement, and the stops 35 stop each box in its proper position for the upper plunger to enter it when it starts on its down stroke, which it does, and carries it down against the gummed blank 10 and the top of the lower plunger.

Having described my invention, what we claim as new and desire to secure by Letters Patent, is:

1. In an automatic box feeding mechanism, the combination with the box receiving plunger of a box wrapping machine, of a box supporting guideway, and means including a cam and rock arm actuated reciprocating plate for intermittently moving 15 a box along said guideway to said plunger, and means including adjustable stop and box centering guides for guiding each box into the path of said plunger, and means including a reciprocating and resilient box 20 supporting lip mechanism actuated to support a box in alinement with said plunger by engagement therewith.

2. In a box feeder for box wrapping machines, the combination with the plunger, 30 of the box receiving slideway, the box pushing plunger arranged to reciprocate therein, resilient controlled reciprocal means including an extension edge supporting shelf for protecting the overhanging edges of extension edge boxes, and means including box 35 stopping guiding and centering guides for directing each box into the path of said plunger.

3. In a box feeder for box wrapping machines, the combination with the plunger, of the box receiving slideway, the box pushing plunger arranged to reciprocate therein, and resilient controlled reciprocal means including an extension edge supporting shelf for 45 protecting the overhanging edges of extension edge boxes, said means also including a bearing plate on said plunger and an adjustable plunger engaging guide arm and roller arranged to control the reciprocal 50 movements of said extension edge supporting shelf.

4. In a box feeder for box wrapping machines, the combination with the plunger, of the box receiving slideway, the box pushing plunger arranged to reciprocate therein, and resilient controlled reciprocal means including an extension edge supporting shelf for 55 protecting the overhanging edges of extension edge boxes, said means also including a bearing plate on said plunger and an adjustable plunger engaging guide arm and roller arranged to control the reciprocal 60 movements of said extension edge supporting shelf, and cam actuated means for operating said box pushing plate.

5. In an automatic box feeding mechanism for box wrapping machines, the combination of the table frame and the upper plunger, with a box feeding mechanism comprising a guideway adapted to receive boxes, 70 and a box pushing reciprocal mechanism arranged to deliver boxes one at a time under said upper plunger, and means including resilient guides for supporting the box below the plunger and for releasing said box 75 when said plunger enters it on the downward stroke of its reciprocal movement.

6. In an automatic box feeding mechanism for box wrapping machines, the combination of the table frame and the upper 80 plunger, with a box feeding mechanism comprising a guideway adapted to receive boxes, a box pushing reciprocal mechanism arranged to deliver boxes one at a time under said upper plunger, and means including a 85 pair of reciprocating cam and spring controlled blades attached to said guide frame for supporting and feeding extension edge boxes to said upper plunger.

7. In an automatic box feeding device for 90 box wrapping machines, the combination with the table frame, the upper plunger provided with a reciprocal movement, of a box receiving guideway, the guides at the side of said guideway for receiving the box, 95 the slideway in said guideway, the cross-head reciprocally mounted in said slideway, provided with a box pushing blade, the cam actuated rock arm and link mechanism for operating said mechanism, and means including adjustable box end engaging stops and resilient box supporting side guides 100 arranged to support each box in the path of said plunger and to release each box after said plunger enters it.

8. In an automatic box feeder for box 105 wrapping machines, the combination with the table frame, the upper plunger, of a box receiving guideway, the guides at the side of said guideway for receiving the box, the 110 slideway in said guideway, the cross-head reciprocally mounted in said slideway, provided with a box pushing blade, the cam actuated mechanism for operating said mechanism, and means including cam blades 115 on said plunger and an adjustable stroke spring actuated lever and shaft controlled extension edge supporting blade for supporting extension edge boxes as said plunger enters them on its box engaging and 120 feeding stroke.

9. The combination with a box wrapping machine having a reciprocating box receiving plunger, of means for delivering boxes to a point in the path of said plunger comprising a support, parallel guideways on said support, an automatically operating box pusher on said support, oppositely arranged box supporting ledges mounted in 125 said guideways in the path of said plunger, 130

and means operated by the plunger for withdrawing said ledges after the plunger enters the box.

10. The combination with a box wrapping machine having a reciprocating plunger, of means for delivering unwrapped boxes to a point in the path of the downward movement of said plunger, comprising a support mounted on said machine, an automatically

10 operating box pusher on said support, parallel guide bars adjustably mounted on said support and extending beneath but out of the path of the ends of said plunger, oppositely disposed box supporting ledges slidably mounted in said guide bars in the path of said plunger, and means operated by said plunger, for withdrawing said ledges after the plunger enters a box.

11. The combination with a box wrapping machine having a reciprocating box receiving plunger, of means for delivering unwrapped boxes to a point in the path of the downward movement of said plunger, comprising a horizontal support on said machine, parallel guide bars mounted on said support and laterally adjustable with respect to each other, said bars extending below the plunger but out of the path of its ends, oppositely positioned box supporting ledges slidably mounted in said guide bars and normally projected into the path of said plunger, a box pusher slidably mounted on said support between said guide bars, a cam and lever mechanism for sliding said pusher to deliver boxes to said ledges, stops on said guides to define the movement of said boxes, and spring controlled lever mechanism operated by said plunger to withdraw said ledges after the plunger enters a box.

40 12. The combination with a box wrapping machine having a reciprocating box receiving plunger, of a support secured to said machine, laterally adjustable parallel horizontal guide bars mounted on said support, 45 below the uppermost position of said plunger, and spaced to permit said plunger to pass between them on its downward move-

ment, oppositely positioned horizontal box supporting ledges slidably mounted in said guide bars and normally projected into the 50 path of said plunger, bearing brackets on said guide bars, shafts mounted in said brackets, depending arms rigidly mounted on said shafts, links connecting said ledges and the lower ends of said arms, upwardly 55 extending arms rigidly mounted on said shafts, horizontal arms adjustably mounted in the upper ends of the upwardly extending arms, having rollers on their inner ends in normal engagement with the ends of the 60 plunger, means for feeding boxes between said guide bars to said box supporting ledges, springs for normally holding said rollers in contact with the ends of the plunger, and inclined plates on the upper edges 65 of the ends of said plunger in the path of said rollers, which permit an inward movement of the roller carrying arms and the consequent rocking of the upright arms, as the plunger enters the box, whereby the 70 depending arms are operated to withdraw the ledges from beneath the box.

13. The combination with a box wrapping machine having a reciprocating box receiving plunger, of a guideway extending across 75 the path of said plunger, opposite box supports in said guideway normally projected into the path of the downward movement of said plunger, automatically operating means for delivering boxes to said support, stops 80 for defining the movement of said boxes, and levers operated by said plunger on its downward movement for retracting said box supports after the plunger enters the box.

85 In testimony whereof we affix our signatures in presence of two witnesses.
